Application February 21, 1946, Serial No. 649,345

11 Claims. (Cl. 178—44)

2

The present invention relates to electrical connectors and, particularly, to electrical connectors which are adapted detachably to engage electrically conductive contact members that may be required to conduct high-frequency electrical currents and relatively large quantities of heat. As used throughout the specification and in the appended claims, the term "high frequency" refers to those frequencies at which alternating currents penetrate but a small portion of the cross-sectional area of a conductor due to skin effect. While the invention has utility in a wide variety of applications, it has particular utility as an electrode-terminal connector for use with electron tubes of the type wherein a heat-conducting electrical terminal thereof has a relatively large surface area for engagement with a corresponding surface area on the connector, and will be described in that connection.

The power output developed by some high-frequency oscillation generators and amplifiers is of considerable magnitude, often requiring that one or more of the electrode terminals of the electron tubes used therein have special constructions and shapes adequately to dissipate from the terminal the heat developed at the electrode due to electron flow thereto. Otherwise the temperature of the electrode or the glass seal at the electrode lead-in conductor may become excessive and cause failure of the glass. Frequently, however, such electron tubes are necessarily mounted within a cavity or coaxial line resonator. This necessitates that the heat developed at the electrodes readily be conducted therefrom, through the medium of the electrical terminal connectors, to the exterior of the cavity resonator where it is dissipated by radiation. This heat transfer is generally effected by providing such electrode terminals with large exterior surface areas for engagement with correspondingly large surface areas on the electrical connectors, thus enabling the latter to receive and rapidly conduct the heat away from the tube.

Prior connectors for use with such terminals have been provided with sufficiently large and firmly engaging surfaces to afford a thermal-conductive path of low thermal resistance from the electron-tube terminal in contact therewith. Experience has shown, however, that important electrical difficulties are encountered with such prior connectors when the surfaces in engagement also comprise a portion of the conductive path of an electrical circuit of a high-frequency arrangement such as an oscillation generator or amplifier.

Although the engagement of such surfaces may

be sufficiently close to provide a good heat transfer, it generally is not sufficiently intimate to afford an electrically conductive circuit path of definite effective path length and consistent low impedance for high frequency currents. Surface conditions such as slight irregularities on the faces of the engaging members, even though these members are constructed to close manufacturing tolerances, form irregular and unpredictable points of electrical contact therebetween which give rise to irregular and unpredictable effective path lengths for high frequency currents. Additionally, since the surface configurations of the terminals of individual tubes ordinarily vary somewhat, an engagement between an electrical connector and the terminal of a replacement tube in an electrical circuit may alter the effective electrical length of that circuit from its original value.

There is an additional difficulty with these prior connectors in that there is a tendency for corrosion, dust or other foreign matter to accumulate on the adjoining surfaces of an electrical connector and an electron-tube terminal of the character described above. These accumulations undesirably increase the resistance at the contacting surface area, particularly over a period of time. Furthermore, since the electrical and thermal circuits are completed by two large surface areas being brought into engagement over a large area, any re-engagement of these surface areas, as by the replacement of an electron tube, leaves the undesirable surface condition on at least one of the surface areas substantially unaffected. Such surface conditions may undesirably and unpredictably increase the effective resistance of an electrical circuit which includes the engaging members.

When such an electrical connector and the electron-tube terminal form a portion of a high-frequency resonant circuit, there may result a lowered or erratic Q for the resonant circuit due to the increased or unpredictable effective resistance last mentioned. Since the Q of a resonant circuit may be defined as the ratio of the total energy in the circuit in a cycle of its operation to the energy dissipated in the cycle, it will be manifest that any increased effective resistance due to the engagement of the connector and tube terminal will increase the circuit losses and, hence, lower the Q of that circuit.

Ultra-short-wave oscillation generators and amplifiers which utilize prior electrical connectors with electron-tube terminals of the thermal-conducting type mentioned above are often

subjected to undesirable frequency instability due in a considerable measure to the electrically conductive paths for high frequency currents being of unstable electrical lengths under operating conditions. Oscillation generators, for example, ordinarily employ one or more resonant transmission lines in the circuits thereof. The operating frequency of the generator is established by adjusting the electrical length of at least one of these transmission lines. These lines include in their effective electrical lengths the paths for the high-frequency electrical currents through the connectors and tube terminals. Thus when a high degree of tuning accuracy is required in a generator of the type mentioned, the presence in the resonant transmission lines of electrical paths having unstable lengths during the operation of the oscillation generator constitutes a serious disadvantage.

It is an object of the present invention, therefore to provide a thermally conductive electrical connector, of the type under consideration, which avoids one or more of the above-mentioned disadvantages and limitations of prior connectors of the type described.

It is a further object of the invention to provide a new and improved electrical connector, adapted detachably to engage an electrical contact member, having a greater thermal conductivity than has been heretofore readily obtainable while insuring an electrically conductive path of definite length and consistently low resistance for high-frequency wave-signal currents.

It is an additional object of the invention to provide a new and improved electrical connector, adapted detachably to engage an electrical contact member and to form therewith a portion of a high-frequency resonant circuit which, while insuring a thermal-conductive path of low thermal resistance, consistently maintains an electrically conductive path of definite length and low value of resistance for high-frequency electrical currents, thus contributing to a high figure of merit or Q for the resonant circuit.

In accordance with one form of the invention, a thermally conductive electrical connector is adapted detachably to engage an electrically conductive contact member and to form therewith a portion of a high-frequency conductive circuit of critical electrical length and resistance. The connector comprises a first thermally conductive member of relatively large mass for firmly yet detachably engaging the contact member over a substantial area thereof and to provide a thermal-conductive path of low thermal resistance and an electrically conductive path which, in the conductive circuit, undesirably has an indefinite path length and value of resistance for high-frequency wave-signal currents due to surface conditions at the areas of engagement of the members. The connector also includes a second electrically conductive member of relatively small mass for electrically yet detachably engaging the contact member intimately over an area thereof smaller than the first-mentioned area to provide an electrically conductive path which, in the conductive circuit, has a definite length and consistently low value of resistance for the high-frequency wave-signal currents. The engagement of the connector and the contact member thus permits a substantial transfer of thermal energy while establishing and maintaining in a definite and consistent manner the critical electrical length and resistance of the conductive circuit.

For a better understanding of the present invention, together with other and further objects thereof, reference is had to the following description taken in connection with the accompanying drawings, and its scope will be pointed out in the appended claims.

Referring now to the drawings, Fig. 1 illustrates a longitudinal sectional view of a high-frequency wave-signal generator which utilizes a thermally conductive electrical connector embodying the present invention; Fig. 2 is an enlarged cross-sectional view of that portion of the generator of Fig. 1 which includes the electrical connector of the present invention; Fig. 3 is a sectional view along the line 3-3 of Fig. 1; and Fig. 4 is a sectional view taken along the line 4-4 of Fig. 1.

Referring now more particularly to Fig. 1 of the drawings, the thermally conductive electrical connector of the present invention is illustrated in connection with a high-frequency wave-signal generator. This generator includes a triode electron tube 10 having suitable external terminals for the individual electrodes. The grid terminal comprises a grid radiator 15 of the type disclosed and claimed in Patent No. 2,439,641, granted April 13, 1948 to Harold A. Wheeler, entitled "An Arrangement for Conducting Heat and High Frequency Currents," and assigned to the same assignee as the instant invention. An annular anode terminal 29 and coaxially arranged heater and cathode terminals 16 and 17, respectively, to be described more fully hereinafter, comprise the remaining terminals of tube 10.

The high-frequency signal generator also includes an anode-grid cavity resonator 19 comprising a cylindrical hollow outer conductor 20 and a cylindrical hollow inner conductor 21, which are maintained in fixed spaced coaxial relationship by insulating spacers 22, 22 secured between the conductors 20 and 21 at points suitably spaced around the circumference thereof. One end of the inner conductor 21 is closed by an electrically conductive cup-shaped connector 23 which is provided with a plurality of arcuate resilient contact fingers 24, the tips of which are adapted conductively to engage the grid radiator 15. Closing the corresponding end of the outer conductor 20 is an annular metal disc 25 and a digitate electrically conductive contact member 26, which form elements of a thermally conductive electrical connector 27 embodying the present invention and hereinafter to be described in greater detail. A plurality of resilient fingers 28 on the member 26 and also the annular disc 25 engage the anode terminal 29 of the triode 10. The other end of the hollow cylindrical outer conductor 20 is closed by a conductive disc 30 which is centrally apertured to receive a conductive cylindrical plunger 31 which slidably engages a plurality of aligning, spring finger, electrical contacts 32, 32. Cylindrical plunger 31 has a diameter appreciably smaller than that of the hollow inner conductor 21 and effectively forms a re-entrant portion of the outer conductor 20 axially movable for the purpose of tuning the cavity resonator 19.

The signal generator also includes an anode-cathode cavity resonator 35 comprising a cylindrical hollow outer conductor 36 and a cylindrical hollow inner conductor 37, which are supported in fixed coaxial relationship by insulating spacers 38, 38 secured between corresponding end walls 39 and 40 of the respective inner and outer conductors. The outer conductor 36 is detachably secured to the outer conductor 20 of cavity reso-

nator 19 by a mechanical coupling arrangement 41, the separable feature of the arrangement being effective to permit the insertion of triode 10. The end of the outer conductor 36 supporting the coupling arrangement 41 has attached thereto, by means of suitable fasteners such as rivets 42 and by soldering a hollow electrically conductive member 43 which forms an additional portion of electrical connector 27. The member 43 has an inner and an outer set of resilient fingers 44, 44 and 45, 45, respectively (see also Fig. 4), which electrically and mechanically engage the anode terminal 29 of triode 10 in a manner more fully to be described subsequently. The proximate end of inner conductor 37 is open to receive triode 10 while the end plate 39 at the opposite end of the inner conductor is apertured to receive and support a hollow conductive cathode post 47. An insulating sleeve 48 maintains an inner conductor 49 in spaced coaxial relationship with the hollow cathode post 47. Attached to the cathode post 47 and the inner conductor 49 is a coaxial connector having resilient fingers 50 and 51 for detachable engagement with the respective cathode terminal 16 and the heater terminal 17 of triode 10. Cathode post 47 and the inner conductor 49 extend outwardly through an aperture 52 in the end wall 40 of the outer conductor 36.

A coupling loop 55, disposed in a position where the magnetic field in the cavity resonator 19 has a maximum value, is conductively secured to the anode disc 25 and is utilized to couple output signals of the oscillation generator to a suitable utilizing circuit 56, which may for example be an antenna. The connector 23 in the grid circuit of triode 10 and the cathode post 47 are interconnected through a T-filter 57 and a grid-leak resistor 58. Filament excitation for the tube 10 is supplied by a transformer 61, the secondary of which is connected to the cathode post 47 and the inner conductor 49 through secondary bifilar windings 59 of a bifilar pulse-modulation transformer 60. The modulation transformer 60, as thus arranged, has its secondary winding 59 connected between the anode and cathode of tube 10, and is connected with such polarity that each modulation pulse causes the cathode to be energized to a negative potential relative to the grounded anode.

The wave-signal generator described above is of a well-known type, the distributed inductance and capacitance of the cavity resonators 19 and 35 replacing the conventional lumped components, which are utilized in low frequency arrangements. The outer conductors 20 and 36 of the oscillation generator and, hence, the anode of triode 10 is maintained at ground potential. Cavity resonator 19 is preferably a half-wave re-entrant structure, while cavity resonator 35, for optimum operation, should be slightly longer than one-quarter wave length at the mean operating frequency of the oscillation generator to afford a capacitive reactance. Since the high-frequency wave-signal currents developed by the oscillation generator travel on the surface of the conductors, the conductive surfaces thereof are preferably silver plated to afford a low value of resistance.

Considering briefly the operation of the above-described oscillation generator, excitation potentials for initiating oscillations are applied with negative polarity to the cathode of triode 10 from the modulation transformer 60. Oscillating voltages developed in the cavity resonator 35 as a result of oscillating cathode current flowing in this

resonator are loosely coupled to cavity resonator 19 through the control electrode-cathode capacitance of triode 10. The oscillation-signal voltages developed at the control electrode end of cavity resonator 19 act to control the cathode current of triode 10 in the proper phase to sustain the oscillation. Wave-signal energy is translated to the utilizing circuit 56 by means of loop 55.

It is a characteristic of an oscillation generator of the type under consideration that the high-frequency conductive circuits thereof have critical electrical lengths and resistances. It will thus be manifest that it is necessary to establish and maintain in a definite and consistent manner the electrical lengths and resistances of each portion of these circuits, including terminal connections to the electron tube, in order to ensure satisfactory performance. Large quantities of heat are developed at the anode electrode of tube 10 and, in order to limit temperature rise thereof, must be conducted away therefrom by the electrical connector 27 detachably engaging the anode terminal 29. At the same time, the connector 27 is included in the high-frequency circuits of both of the cavity resonators 19 and 35. Additional problems are thus encountered as a result of the dual function of the electrical connector 27. For a clear understanding thereof, consider now with greater particularly the portion of the described oscillation generator which embodies the connector 27 of the instant invention, an enlarged axial sectional view thereof being illustrated in Fig. 2 of the drawings. The triode 10, employed in the generator, has coaxially arranged elements comprising an axially disposed cylindrical cathode 11, a control electrode 12 in the form of a cage, and an outer cylindrical anode 13. The control electrode 12 and the cathode 11 are arranged in an evacuated enclosure comprising a glass envelope 14. The cylindrical anode has metal-to-glass seals with the envelope as indicated. The annular disc 25 of electrical connector 27 comprises a first member which is adapted firmly to engage a contact member, comprising the anode terminal 29 of triode 10, over a substantial area thereof to provide a thermal-conductive path of low thermal resistance. The disc 25 also provides an electrical-conductive path which, in the conductive circuit of cavity resonator 19, has an indefinite path length and value of resistance for high-frequency wave-signal currents due to surface conditions at the areas of engagement of the annular disc 25 and the anode terminal 29. A detailed explanation of the causes underlying the last statement regarding the indefiniteness of the effective path length and resistance resulting from the engagement of annular disc 25 and the anode terminal 29 will be presented subsequently.

Anode terminal 29 has a relatively large mass and a high thermal conductivity substantially to assist in reducing the operating temperature of the anode electrode 13. For this purpose, the terminal 29 is provided with a relatively smooth flat surface area on the side which closely engages a corresponding surface area on the thermally conductive annular disc 25, thus affording effective conduction of heat therebetween.

In view of the previously mentioned indefinite electrical path length for high-frequency wave-signal currents which is undesirably provided by the annular disc 25 and the anode terminal 29, the electrical connector 27 also includes a second member comprising the digitate member 28 which

has a plurality of resilient fingers 65, 65. These fingers are individually adapted intimately to engage the anode terminal 29 over an area thereof smaller than that area of annular disc 25 which is in mechanical and thermal engagement with anode terminal 29. A skirt 66 on member 26 is secured to the outer conductor 20 by fasteners 67 and also is soldered thereto to ensure a low resistance connection. The intimate engagement of resilient fingers 65 with the anode terminal 29 causes the digitate member 26 to afford with certainty an electrical-conductive path which, in the oscillation-generator frequency-determining circuit comprising cavity resonator 19 extending between the anode and control electrodes of triode 10, has a definite length and consistently low value of resistance for high-frequency wave-signal currents. The reasons for this will be explained more fully hereinafter. The free ends of fingers 65 extend radially inwardly for a short distance toward the axis of the oscillator, as represented in Fig. 3 of the drawings. When the tube 10 is removed from engagement with the fingers 65, the latter project beyond the terminal-engaging surface of anode disc 25. The engagement of the fingers with terminal 29 thus is effective to force them radially inwardly, thereby providing a scraping or cleaning action between the tips of fingers 65 and the surface of substantially rigid anode terminal 29. This ensures a good electrical connection between the fingers and the terminal.

Resilient fingers 45 of conductive member 43 on the other portion of electrical connector 27 are adapted to receive therebetween and engage the peripheral face of anode terminal 29, as illustrated in Fig. 2. Resilient fingers 44 are adapted to make a good electrical contact with the anode terminal 29 in a manner similar to that of the fingers 65. Since fingers 44 are in the conductive circuit of cavity resonator 35, it will be manifest that the mechanical coupling means 41 and the conductive member 43 comprise means for maintaining the anode terminal 29 of tube 10 firmly in engagement with annular disc 25 and the digitate member 26 while aiding in establishing a second electrical-conductive path of definite path length and consistent low value of resistance for high-frequency wave-signal currents. Resilient fingers 44 and 45 are also effective to support the tube 10 and orient the engaging surface of anode terminal 29 with respect to the corresponding surface of anode disc 25.

Reference is now made to Fig. 2 of the drawings for a consideration of the possible electrically conductive paths for high-frequency wave-signal currents through the portions of the detachable electrical connector 27. For the purpose of explanation, portions of two such high-frequency current paths in the cavity resonator 19 are illustrated by broken lines and, for convenience, these portions are designated and will be referred to hereinafter as path A and path B. Path B represents a desirable path for radio frequency currents. Path A denotes an undesirable electrical path extending through the thermally conductive region. Paths such as path A are avoided by the connector of the instant invention.

At high frequencies, the current travel is on the surface or skin of a conductor rather than through the interior thereof as at lower frequencies. Path A illustrates the travel of radio frequency currents from the inner surface of outer conductor 20 along the surface of annular disc 25 to some point C of satisfactory electrical contact

between the disc 25 and the anode terminal 29. Path A continues from point C along one surface of the anode terminal 29 to anode electrode 13 where the current follows the outer surface thereof prior to traversing the anode-cathode space of tube 10. Point C is intended to represent a surface irregularity, such as a high spot on either or both of the engaging members 25 and 29, or a clean low resistance spot between them. It will be manifest that the exact location of spot C on the relatively large, flat, engaging surfaces of members 25 and 29 will be unpredictable due to the random disposition of small surface irregularities and accumulations of foreign matter on the abutting surfaces. The frequency of the high-frequency resonant circuit comprising cavity resonator 19 depends upon the effective electrical length of the transmission line including the outer and inner conductors 20 and 21 and the anode and control-electrode terminal connections associated therewith. Hence, a slight variation in the electrical length of this conductive circuit, as with tube changes or due to mechanical vibration of the generator, may result in an appreciable change in operating frequency of the generator. It may also be noted that while the effective high frequency current path includes the point C, the resistance presented by that point may have a higher value than is desired due to corrosion or other surface accumulations on the engaging members 25 and 29. This value of resistance may impair the figure of merit or Q of the cavity resonator 19 since the energy dissipated during each alternating current cycle is increased with any such increase of contact resistance. Hence, path A undesirably has an indefinite path length and indefinite value of resistance for high frequency currents. It is imperative for adequate stability of operating frequency and operating characteristics of the generator that an electrically conductive path in any portion of the conductive circuit of cavity resonator 19, particularly the conductive path between outer conductor 20 and the anode terminal 29, have a definite length and definite impedance during the operation of the arrangement.

Digitate member 26 with its resilient fingers 65 affords the shorter electrically conductive path B as previously mentioned, the fingers 65 provide a scraping or self-cleaning action each time they newly engage the anode terminal 29. Path B, therefore, has a definite length and consistently low value of resistance for high frequency currents. These characteristics are enhanced by the fact that the tips of resilient fingers 65 contact but a small portion of the area of anode terminal 29. Since path A is considerably longer than path B, the higher inductance of the former causes the major portion of high frequency currents to follow path B. Because the engaging region between the fingers 65 and anode terminal 29 is always definitely known, the electrical connector 27 establishes and maintains in a consistent manner several desirable electrical characteristics of the cavity resonator 19, namely, frequency stability and a high Q. At the same time, the connector 27 conducts large amounts of thermal energy to the heat-dissipating outer conductors 20 and 36.

It will be clear from the foregoing explanation that the resilient conductive fingers 44 of member 43 in the conductive circuit of cavity resonator 35 serve a function similar to that of the resilient fingers 65 on the digitate member 26. The combined effect of the several portions of the electrical connector results in improved performance

by the high-frequency oscillation generator associated therewith. Fingers 44 have the additional important function of biasing the anode terminal 29 into firm engagement with the annular disc 25 and the contact fingers 65 to ensure that the latter consistently have the desirable characteristics last described.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A thermally conductive electrical connector adapted detachably to engage an electrically conductive contact member and to form therewith a portion of a high-frequency conductive circuit of critical electrical length and resistance comprising, a first thermally conductive member of relatively large mass for firmly yet detachably engaging said contact member over a substantial area thereof to provide a thermal-conductive path of low thermal resistance and an electrically conductive path which in said conductive circuit undesirably has an indefinite effective path length and value of resistance for high-frequency wave-signal currents due to surface conditions at the areas of engagement of said members, and a second electrically conductive member of relatively small mass for electrically yet detachably engaging said contact member intimately over an area thereof smaller than said first-mentioned area to provide an electrically conductive path which in said conductive circuit has a definite length and consistently low value of resistance for said high-frequency wave-signal currents, whereby the engagement of said connector and said contact member permits substantial transfer of thermal energy therebetween while establishing and maintaining in a definite and consistent manner said critical electrical length and resistance of said conductive circuit.

2. A thermally conductive electrical connector adapted detachably to engage an electrically conductive contact member and to form therewith a portion of a high-frequency conductive circuit of critical electrical length and resistance comprising, a first thermally conductive and substantially rigid member of relatively large mass for firmly yet detachably engaging said contact member over a substantial area thereof to provide a thermal-conductive path of low thermal resistance and an electrically conductive path which in said conductive circuit undesirably has an indefinite effective path length and value of resistance for high-frequency wave-signal currents due to surface conditions at the areas of engagement of said members, and a second electrically conductive resilient member of relatively small mass for yieldingly yet detachably engaging said contact member intimately over an area thereof smaller than said first-mentioned area to provide an electrically conductive path which in said conductive circuit has a definite length and consistently low value of resistance for said high-frequency wave-signal currents, whereby the engagement of said connector and said contact member permits substantial transfer of thermal energy therebetween while establishing and maintaining in a definite and consistent manner said critical electrical length and resistance of said conductive circuit.

said critical electrical length and resistance of said conductive circuit.

3. A thermally conductive electrical connector adapted detachably to engage a relatively smooth surface on an electrically conductive contact member and to form therewith a portion of a high-frequency conductive circuit of critical electrical length and resistance comprising, a first thermally conductive member of relatively large mass having a relatively smooth surface area for firmly yet detachably engaging a corresponding relatively smooth surface area on said contact member over a substantial area thereof to provide a thermal-conductive path of low thermal resistance and an electrically conductive path which in said conductive circuit undesirably has an indefinite effective path length and value of resistance for high-frequency wave-signal currents due to surface conditions at the areas of engagement of said members, and a second electrically conductive member of relatively small mass for electrically yet detachably engaging said relatively smooth surface area on said contact member intimately over an area thereof smaller than said first-mentioned area to provide an electrically conductive path which in said conductive circuit has a definite length and consistently low value of resistance for said high-frequency wave-signal currents, whereby the engagement of said connector and said contact member permits substantial transfer of thermal energy therebetween while establishing and maintaining in a definite and consistent manner said critical electrical length and resistance of said conductive circuit.

4. A thermally conductive electrical connector adapted detachably to engage a relatively flat surface area on an electrically conductive contact member and to form therewith a portion of a high-frequency conductive circuit of critical electrical length and resistance comprising, a first thermally conductive member of relatively large mass having a relatively flat surface area for firmly yet detachably engaging a corresponding relatively flat surface area on said contact member over a substantial area thereof to provide a thermal-conductive path of low thermal resistance and an electrically conductive path which in said conductive circuit undesirably has an indefinite effective path length and value of resistance for high-frequency wave-signal currents due to surface conditions at the areas of engagement of said members, and a second electrically conductive member of relatively small mass for electrically yet detachably engaging said relatively flat surface area on said contact member intimately over an area thereof smaller than said first-mentioned area to provide an electrically conductive path which in said conductive circuit has a definite length and consistently low value of resistance for said high-frequency wave-signal currents, whereby the engagement of said connector and said contact member permits substantial transfer of thermal energy therebetween while establishing and maintaining in a definite and consistent manner said critical electrical length and resistance of said conductive circuit.

5. A thermally conductive electrical connector adapted detachably to engage an annular electrically conductive contact member and to form therewith a portion of a high-frequency conductive circuit of critical electrical length and resistance comprising, an annular first thermally conductive member of relatively large mass for firmly yet detachably engaging said contact member over a substantial area thereof to pro-

vide a thermal-conductive path of low thermal resistance and an electrically conductive path which in said conductive circuit undesirably has an indefinite effective path length and value of resistance for high-frequency wave-signal currents due to surface conditions at the areas of engagement of said members, and a digitate electrically conductive second member of relatively small mass for electrically yet detachably engaging said contact member intimately over an area thereof smaller than said first-mentioned area to provide an electrically conductive path which in said conductive circuit has a definite length and consistently low value of resistance for said high-frequency wave-signal currents, whereby the engagement of said connector and said contact member permits substantial transfer of thermal energy therebetween while establishing and maintaining in a definite and consistent manner said critical electrical length and resistance of said conductive circuit.

6. A thermally conductive electrical connector adapted detachably to engage an electrically conductive contact member and to form therewith portions of a plurality of high-frequency conductive circuits of critical electrical lengths and resistances comprising, a first thermally conductive member of relatively large mass for detachably engaging said contact member over a substantial area thereof to provide a thermal-conductive path of low thermal resistance and electrically conductive paths which in said conductive circuits undesirably have indefinite effective path lengths and values of resistance for said high-frequency wave-signal currents due to surface conditions at the areas of engagement of said members, second and third electrically conductive members of relatively small mass for electrically yet detachably engaging said contact member intimately over an area thereof smaller than said first-mentioned area to provide an electrically conductive path which in an individual one of said conductive circuits has a definite length and a consistently low value of resistance for said high-frequency wave-signal currents, and means including said third member for maintaining said contact member firmly in engagement with said first and second members, whereby the engagement of said connector and said contact members permits substantial transfer of thermal energy therebetween while establishing and maintaining in a definite and consistent manner said critical electrical lengths and resistances of said conductive circuits.

7. A thermally conductive electrical connector adapted detachably to engage an electrically conductive contact member and to form therewith portions of a plurality of high-frequency conductive circuits of critical electrical lengths and resistances comprising, a first thermally conductive member of relatively large mass for detachably engaging said contact member over a substantial area thereof to provide a thermal-conductive path of low thermal resistance and electrically conductive paths which in said conductive circuits undesirably have indefinite effective path lengths and values of resistance for said high-frequency wave-signal currents due to surface conditions at the areas of engagement of said members, second and third electrically conductive members of relatively small mass for electrically yet detachably engaging said contact member intimately over an area thereof smaller than said first-mentioned area to provide an electrically conductive path which in an individ-

ual one of said conductive circuits has a definite length and a consistently low value of resistance for said high-frequency wave-signal currents, and means including said third member for orienting and maintaining said contact member firmly in engagement with said first and second members, whereby the engagement of said connector and said contact members permits substantial transfer of thermal energy therebetween while establishing and maintaining in a definite and consistent manner said critical electrical lengths and resistances of said conductive circuits.

8. A thermally conductive electrical connector adapted detachably to engage an electrically conductive contact disc and to form therewith a portion of a high-frequency conductive circuit of critical electrical length and resistance comprising, a first thermally conductive member of relatively large mass for detachably engaging one face of said contact disc over a substantial area thereof to provide a thermal-conductive path of low thermal resistance and an electrically conductive path which in said conductive circuit undesirably has an indefinite effective path length and value of resistance for high-frequency wave-signal currents due to surface conditions at the areas of engagement of said members, a second electrically conductive member of relatively small mass for electrically yet detachably engaging one face of said contact disc intimately over an area thereof smaller than said first-mentioned area to provide an electrically conductive path which in said conductive circuit has a definite length and consistently low value of resistance for said high-frequency wave-signal currents, and means engaging the periphery and the other face of said contact disc for orienting said one face of said contact disc with respect to said first and second members and for maintaining a firm engagement between said contact disc and said members, whereby the engagement of said connector and said contact disc permits substantial transfer of thermal energy therebetween while establishing and maintaining in a definite and consistent manner said critical electrical length and resistance of said conductive circuit.

9. A thermally conductive electrical connector adapted detachably to engage an electrically conductive contact member and to form therewith a portion of a high-frequency resonant circuit of critical electrical length and resistance comprising, a first thermally conductive member of relatively large mass for firmly yet detachably engaging said contact member over a substantial area thereof to provide a thermal-conductive path of low thermal resistance and an electrically conductive path which in said resonant circuit undesirably has an indefinite effective path length and value of resistance for high-frequency wave-signal currents due to surface conditions at the area of engagement of said members, and a second electrically conductive member of relatively small mass for electrically yet detachably engaging said contact member intimately over an area thereof smaller than said first-mentioned area to provide an electrically conductive path which in said resonant circuit has a definite length and consistently low value of resistance for said high-frequency wave signal currents, whereby the engagement of said connector and said contact member permits a substantial transfer of thermal energy therebetween while establishing and maintaining in a definite and consistent manner

the electrical characteristics of said resonant circuit.

10. A thermally conductive electrical connector adapted detachably to engage an electrically conductive contact member and to form therewith a portion of a high-frequency cavity resonator of critical electrical length and resistance comprising, a first thermally conductive member of relatively large mass for detachably engaging said contact member over a substantial area thereof to provide a thermal-conductive path of low thermal resistance to the exterior of said cavity resonator and an electrically conductive path which in said cavity resonator undesirably has an indefinite effective path length and value of resistance for high-frequency wave-signal currents due to surface conditions at the areas of engagement of said members, and a second electrically conductive member of relatively small mass for electrically yet detachably engaging said contact member intimately over an area thereof smaller than said first-mentioned area to provide an electrically conductive path which in said cavity resonator has a definite length and consistently low value of resistance for said high-frequency wave-signal currents, whereby the engagement of said connector and said contact member permits substantial transfer of thermal energy therebetween and to the exterior of said cavity resonator while establishing and maintaining in a definite and consistent manner said critical electrical length and resistance of said cavity resonator.

11. A thermally conductive electrical connector adapted detachably to engage an electrical terminal of an electron tube and to form with said terminal a portion of a conductive circuit of critical electrical length and resistance in a high-frequency wave-signal translating arrangement comprising, a first thermally conductive member of relatively large mass for detachably

engaging said terminal over a substantial area thereof to provide a thermal-conductive path of low thermal resistance and an electrically conductive path which in said conductive circuit undesirably has an indefinite effective path length and value of resistance for high-frequency wave-signal currents due to surface conditions at the areas of engagement of said terminal and said member, a second electrically conductive member of relatively small mass for electrically yet detachably engaging said terminal intimately over an area thereof smaller than said first-mentioned area to provide an electrically conductive path which in said conductive circuit has a definite length and a consistently low value of resistance for said high-frequency wave-signal currents, and means for supporting said tube and for maintaining said terminal firmly in engagement with said first and second members, whereby said engagement of said connector and said terminal permits a substantial transfer of thermal energy therebetween while establishing and maintaining in a definite and consistent manner said critical electrical length and resistance of said conductive circuit in said wave-signal translating arrangement.
